UNITED STATES PATENT OFFICE.

JOHN PRUE KARNS, OF BOULDER, COLORADO, ASSIGNOR TO THE J. P. KARNS TUNNELING MACHINE CO., OF BOULDER, COLORADO.

DRILL-HEAD AND CUTTER-BLADE THEREFOR.

No. 883,137.

Specification of Letters Patent. Patented March 24, 1908.

Original application filed February 23, 1907, Serial No. 358,867. Divided and this application filed June 8, 1907. Serial No. 377,981.

To all whom it may concern:

Be it known that I, JOHN PRUE KARNS, a citizen of the United States, residing at Boulder, in the county of Boulder and State 5 of Colorado, have invented a new and useful Drill-Head and Cutter-Blade Therefor, of which the following is a specification.

This invention has reference to improvements in drill-heads for drilling machines 10 and cutter blades therefor, and it is designed more particularly for use in connection with a drilling machine such as shown and described in my application for Letters Patent No. 358,867, filed February 23, 1907, of 15 which this case is a division. In the said application there is shown a drilling machine designed for the drilling of large bores, up to eighteen or more feet in diameter, through earthy and rock formations. In a machine 20 of the larger type the structure is necessarily very massive and is made to stand heavy strains and hammer blows of great force.

The present invention is directed more particularly to the construction of the drill- 25 head and the cutter blades carried thereby, whereby the drill-head may be made to sustain the effect of heavy blows without injury to itself and the cutter blades may be so supported that they are unaffected by the 30 impact of the material at the breast of the tunnel except insofar as they may become dulled by use, and for this purpose are made readily removable so that they may be sharpened from time to time.

In addition to these features, the invention 35 comprises means whereby the bore of the tunnel may be maintained sensibly constant, and for this purpose there may be provided reamer blades at the periphery of the 40 drill-head so adjustably mounted that they may be projected from their seats from time to time to provide for wear. In order that there may be a practical constancy of the bore of the tunnel produced by the machine 45 all the reamer blades are made adjustable but some are made more finely adjustable than others, so that it is not necessary to adjust all the reamer blades fully every time and the saving therefrom is therefore material. For this purpose a certain small number 50 of the reamer blades may be provided with a fine or delicate adjustment, whereby the wear may be taken up at frequent inter-

vals and in small amounts, while the remainder of the reamer blades are provided with a 55 coarse or gross adjustment, whereby they may be adjusted step by step, each step including the total of a number of successive 60 adjustments of the first-mentioned reamer blades.

Furthermore, the present invention comprises means whereby the cutting teeth provided on the cutter blades carried by the drill-head are so disposed that while all the teeth will move through curved paths during 65 the operation of drilling, each tooth on one blade will travel in an arc falling between two teeth on the next adjacent blades, so that all portions of the end wall or breast of 70 the tunnel being bored will be acted upon by the teeth on the face of the drill-head.

The invention will be fully understood from the following detailed description, taken in connection with the accompanying drawings forming part of this specification, 75 in which,—

Figure 1 is a face view of the drill-head, showing but a few of the cutters in position; Fig. 2 is a central section, with parts in elevation, of the drill-head; Fig. 3 is a view of a 80 portion of one of the reamer blades on a larger scale than shown in Figs. 1 and 2; Fig. 4 is a section through one of the cutter blades and so much of the drill-head as is necessary to show the mode of connecting the cutter 85 blades thereto on about the same scale as Fig. 3; and Fig. 5 is a view of another type of reamer blade, showing the means for producing a fine adjustment thereof on about the same scale as Figs. 3 and 4. 90

Referring to the drawings, the drill-head consists of a spider of a diameter a little less than the bore of the tunnel to be cut. This drill-head spider comprises a hub 1 from which project a number of radial arms 2 integral with a number of concentric rings 3, the outer one of which constitutes the periphery of the drill-head spider. Each arm 2 has formed on its rear face as an integral part thereof a web 4, and each ring 3 has formed on it a rearwardly projecting web 5. The hub, arms, rings and webs are all formed as one integral whole except that the entire structure may, for convenience in manufacturing, be formed of two halves secured together after the manner of split pulleys or

balance wheels. This latter structure is illustrated in Fig. 1. Each web 4 extends from its corresponding arm to the rear end of the hub 1 at the point of junction of these two parts, and such web is of gradually decreasing width toward the periphery of the drill-head to a point near the web 5 on the outer ring 3. At this point the web 4 gradually widens until it merges into the web 5 of the outer ring 3, which last-named web extends to the rear so far as the rear edge of the hub 1. About midway of the outer web 5 and formed on its inner face so as to project radially inward toward the center of the drill-head is a short, strengthening web 6. The structure just described is such that the drill-head spider is braced in all directions against such strains as may come against its front face, and the bracing is such that no strain that may be brought to bear on any portion of said front face will be sufficient to sensibly deflect it from a substantially true plane.

The hub 1 is provided with a boss 7 projecting beyond the front face of the drill-head, and on the front face of this boss are mounted cutter blades 8 at right angles to each other and extending diametrically across the face of said boss.

Secured to the arms 2 tangentially to the boss 8 are a number of cutter blades 9 of sufficient length to span two arms, as shown, and beyond these tangential blades each arm carries a series of blades 10 parallel to the blades 9, and still further toward the periphery of the drill-head each arm has another set of parallel cutter blades 11, shorter than the blades 10 and set at a slightly flatter angle to the arc described by all the blades as the drill-head rotates.

Now, it has already been stated that for structural reasons the drill-head may be made of two halves after the manner of an ordinary split wheel or pulley, and the meeting edges of these two halves are formed with arms 2 of less width than the other arms 2 but the combined width of two contiguous arms is greater than that of any single arm 2 elsewhere located. For this reason the cutter blades 9, 10, and 11 secured to these particular arms are somewhat longer than those secured to the other arms so as to straddle the intervening space between the two meeting arms.

Between the arms 2 the drill-head is provided with a number of radial cutter blades 12 extending from the innermost ring 3 to the next adjacent outer ring 3, and from the latter ring to the peripheral ring 3 are a number of other cutter blades 13, all of which latter are adjustable radially outward and constitute reamer blades, as will hereinafter appear. The several blades of the drill-head are secured to the spider by means best shown in Fig. 4.

In Fig. 4 only one of the arms 2 is shown but this will be sufficient to illustrate the manner of fastening the cutter blades to the drill-head, although these blades are carried both by the arms 2 and the rings 3. Formed in the outer face of the arm 2 is a groove 14 arranged at a suitable angle to receive the inner edge of one of the cutter blades, say a cutter blade 10. At one side of the groove 14 the arm 2 is formed with a rib 15, not shown in Fig. 4 but clearly shown in Fig. 1, and this rib terminates in an enlargement 16 through which extends a perforation to the rear face of the arm 2, which perforation receives the shank of an L-shaped bolt 17. That is, this bolt has one end 18 bent at right angles and seated in a perforation 19 in the cutter blade 10. The other end of the bolt 17, where it extends through the inner face of the arm 2, is threaded to receive a nut 20 by means of which the bolt 17 is secured to the arm 2 in a manner to hold the cutter blade firmly seated in the groove 14. By reference to Fig. 1 it will be seen that each blade is held to the drill-head by two or more bolts 17. While this forms a secure fastening for the cutter blades they are at the same time easily removed from the drill-head by unscrewing the nut 20, when the cutter blades may be lifted from their seats and so taken off from the drill-head.

All the cutter blades are formed with teeth 21, best shown in Fig. 4 where it will be seen that they are generally frusto-pyramidal in shape with an elongated rectangular base and an elongated cutting edge.

Those radial cutter blades 13 which are termed reamer blades extend beyond the outer ring 3 of the drill-head and are there supported by brackets 22 integral with the outer ring 3 and projecting outward therefrom in a radial direction. These brackets have grooves like the groove 14 of Fig. 4 and also have ribs 15 for receiving and supporting the cutter blades. The brackets 22 serve as supports for those portions of the reamer blades which project beyond the periphery of the outer ring 3. The reamer blades project radially outward a short distance beyond the outer ends of the brackets 22 and thereby provide ample clearance for the drill-head outside the brackets 22. At the outer ends the reamer blades are provided with radially projecting reamer teeth 23 in addition to the teeth 21, which latter are like those of the other blades. The reamer blades are cut away to the rear of the teeth 23, as indicated at 24, so as to provide clearance space and also to provide for the wear of these teeth. The extent of radial projection of the teeth 23 of the reamer blades beyond the brackets 22 will determine the diameter of the bore of the tunnel as cut by the drill-head.

In the operation of the machine the teeth 23 will be gradually worn off on their radially

outward edges, and provision is therefore made for adjusting the reamer blades radially outward. In order to facilitate the adjustment of these blades there is provided a fine adjustment for some of them and a coarse adjustment for others. For instance, a certain few, say four, of the reamer blades 15 equi-distantly arranged around the periphery of the drill-head are provided with smooth, longitudinal slots 25, as shown in Fig. 5, for the reception of the ends 18 of the bolts 17, and the rear faces of these particular blades are provided with one or more lugs 26 against which abuts an adjusting set-screw 27 suitably threaded through a fixed stud 10 on an appropriate portion of the drill-head. By simply loosening the nuts 20 of the bolts 17 a very delicate adjustment of the four special reamer blades illustrated may be 20 made in a radially outward direction, when the nuts 20 may be again tightened. This adjustment may be made again and again, as occasion may require, and in practice will be made at comparatively frequent intervals.

25 The rest of the reamer blades 13 are provided with similar slots 28, as best shown in Fig. 3, but instead of these slots being smooth, as shown in Fig. 5, their bottom walls are formed into a series of curved seats 30 29 all of such size as to receive and seat the heads 18 of the bolts 17. These last-named reamer blades can, therefore, be adjusted only step by step, each step representing a movement equal to the diametric thickness 35 of the head 18 of a bolt 17. Now, by adjusting the reamer blades having the smooth slots the diameter of the bore of the tunnel may be kept substantially true, but the reamer blades provided with the coarse adjustment will be 40 wearing away and becoming shorter and shorter. Ultimately, this wearing away will be equivalent to the width of one of the seats 29, or, in other words, to the width of the head 18 of a bolt 17. When this occurs, 45 all of these coarsely adjustable reamer blades can be moved radially outward a distance equal to the thickness of the head 18 of a bolt 17 and then again locked in the adjusted position.

50 The brackets 22 are provided at the rear with webs 30 integral with the webs 6, for imparting strength to the brackets, and these webs are so spaced as to leave room between them for the nuts 20 of the bolts 17, 55 which are provided for fastening the outer ends of the reamer blades to the drill-head.

In order that the teeth of the cutter blades may reach every portion of the surface to be cut, the teeth on adjacent cutter blades are 60 arranged to move, as the drill-head rotates, in arcs interposed between the arcs described by the teeth of adjacent cutter blades.

It will be observed that the cutters on the 65 boss 7 project further forward than those on

the rest of the drill-head. This will cause the drill-head to cut an axial or guiding passage into the end wall of the tunnel in advance of the main portion of the drill-head, thus serving to lead the drill-head and maintain it in the plane of travel determined upon.

70 The drill-head is supported upon one end of a shaft 31 having a stepped end 32 introduced into the hub 1 and there held by a pin 33, but this structure need not be here particularly described since it is fully described in my aforesaid application.

75 As to the manner of operating the drill-head, it may be here stated that the shaft is reciprocated to the desired extent and slowly rotated step by step and is also fed to the breast of the tunnel as the latter is cut away, and the teeth 21 and 23 operate upon the material to be cut after the manner of a stone 80 mason's chisel.

I claim:—

1. In a drilling machine, a drill-head provided with radial cutter blades projecting beyond the periphery of the drill-head to 90 constitute reaming members thereof and adjustable radially to maintain a predetermined diameter of cut.

2. In a drilling machine, a drill-head provided with radial reaming cutters having a 95 fine radial adjustment, and other reaming cutters having a coarse or quick radial adjustment.

3. In a drilling machine, a drill-head provided with cutters adjustable radially beyond 100 the periphery of the drill-head, and provided with adjusting means for the gradual projection of said cutters in a radial direction.

4. In a drilling machine, a drill-head having reaming cutters projecting radially beyond the periphery of the drill-head, and means for the adjustment of said cutters step by step radially outward.

5. In a drilling machine, a drill-head provided with cutters projecting radially outward from the periphery of the drill-head and having means for the fine or gradual adjustment of the same in a radially outward direction, and other cutters projecting radially outward from the periphery of the drill-head and having means for the coarse or step by step adjustment of the same radially outward upon the drill-head.

6. In a drilling machine, a drill-head having reaming cutters projecting radially outward from the periphery of the drill-head, slots in said cutters for the reception of securing means and permitting longitudinal movement of said cutters with reference to said securing means, adjusting screws for 125 moving said cutters gradually outward in a radial direction, and other cutters projecting radially beyond the periphery of the machine and provided with slots for the reception of securing means, said slots being provided in 130

one wall with a series of seats for said securing means whereby the cutters may be adjusted radially outward step by step.

7. In a drilling machine, a drill-head provided with cutter blades, and means for securing said blades thereto comprising L-shaped bolts with their shanks passing through the body of the drill-head and their heads engaging in perforations in the cutter blades.

8. In a drilling machine, a drill-head, series of perforated cutter blades seated in grooves formed in the face of said drill-head, and L-shaped locking bolts having their heads engaging in the perforations in the cutter blades and their shanks projecting through the drill-head to the rear thereof and there receiving securing nuts.

9. In a drilling machine, a drill-head having slotted cutter blades, L-shaped bolts having heads engaging said slots in said cutter blades and their shanks extending through to the rear of the drill-head and there receiving securing nuts, and means for adjusting said blades in the direction of the length of the slots.

10. In a drilling machine, a drill-head, cutter blades mounted therein and provided with slots having one wall formed into seats, and L-shaped securing bolts having their heads projecting into one of the seats in the slots and their shanks extended through to the rear of the drill-head and there receiving securing nuts.

11. In a drilling machine, a drill-head frame consisting of a hub, radial arms projecting therefrom, concentric rings connecting said arms, the outer ring forming the

periphery of the drill-head frame, rearwardly projecting webs upon the ring, the web of the outermost ring having a rearward projection equal to that of the hub and the webs of the other rings having a less extent of rearward projection, and radial webs on the arms having a gradually lessening extent of rearward projection from the hub to near the periphery of the frame and then increasing in rearward projection until they merge into the web formed on the outermost ring, all the said webs, arms and rings being integral at meeting points.

12. In a drilling machine, a drill-head having radial series of angularly-disposed toothed blades and other radially-disposed toothed blades arranged between the angular series of blades, the arrangement being such that the paths of the teeth of one blade are interspersed between the paths of the teeth of the adjacent blades.

13. In a drilling machine, a drill-head having a circular series of spaced groups of radially disposed toothed blades, and other radial series of angularly disposed toothed blades interspersed between the groups of radial blades, the angular disposition of the angularly disposed blades being flatter toward the periphery of the drill-head than near the center thereof.

In testimony that I claim the foregoing as my own, I have hereto affixed my signature in the presence of two witnesses.

JOHN PRUE KARNS.
